UNITED STATES PATENT OFFICE.

VANDIVER J. VAN HORN, OF CHICAGO, ILLINOIS, ASSIGNOR TO UNION SPECIAL MACHINE COMPANY, OF CHICAGO, ILLINOIS, A CORPORATION OF ILLINOIS.

ORNAMENTAL SEAM FOR SEWED ARTICLES.

1,100,507.

Specification of Letters Patent. Patented June 16, 1914.

Application filed February 13, 1911. Serial No. 608,369.

To all whom it may concern:

Be it known that I, VANDIVER J. VAN HORN, a citizen of the United States, residing at Chicago, in the county of Cook, State 5 of Illinois, have invented certain new and useful Improvements in Ornamental Seams for Sewed Articles, of which the following is a description, reference being had to the accompanying drawing and to the letters 10 and figures of reference marked thereon.

The invention relates to ornamental seams for sewed articles.

The object of the invention is to provide a fabric with a plurality of lines of stitching 15 and with an ornamental thread which is laid into oppositely disposed loops secured by said lines of stitching and also with additional ornamental barring threads extending along the lines of stitching.

20 In the drawings:—Figure 1 is a plan view of a portion of fabric having my ornamental seam formed therein. Fig. 2 is an enlarged detail of the seam shown in Fig. 1 with the fabric omitted. Fig. 3 is a view 25 similar to Fig. 2, showing a slightly modified position of the threads.

The fabric 1, is provided with two parallel lines of stitching 2 and 3. The needle punctures in the line of stitching 2 are indicated at 4, while the needle punctures in the line of stitching 3 are indicated at 5. An ornamental thread 6 is formed into half twisted loops which are oppositely disposed and the loops on one side of the seam are 30 entered by alternating needle punctures, while the loops on the other side of the seam are entered by alternate needle punctures in the line of stitching at this side of the seam.

40 An ornamental barring thread 7, as shown in Fig. 2, is laid along the line of stitching 2, passing from one side thereof to the other, and underneath the threads joining consecutive stitches. The barring thread 8, is 45 laid along the line of stitching 3, in a manner similar to the barring thread 7. In said figure, the barring threads 7 and 8 have the appearance of a waving line extending in and out across the line of stitching and extending around the loops in the ornamental 50 thread 6.

In Fig. 3, I have shown the tension on the ornamental threads 7 and 8 as sufficient so as to hold said threads straight while the threads between consecutive needle punctures in the line of stitching 2, are looser and therefore, arrange themselves so as to extend in a zigzag direction back and forth across the ornamental thread 7. The threads in the line of stitching 3 are arranged in a zigzag course similar to the threads in the line of stitching 2.

Having thus particularly described my invention, what I claim as new and desire to secure by Letters Patent is:

1. An ornamental seam for sewed articles, including a fabric, a plurality of parallel lines of stitching, an ornamental thread formed in a series of oppositely disposed half twisted loops secured by said line of stitching to said fabric, and independent side barring threads secured by the lines of stitching to the said fabric.

2. An ornamental seam for sewed articles, including a fabric, a plurality of lines of stitching, an ornamental thread formed in a series of oppositely disposed half twisted loops secured by said lines of stitching to said fabric, a barring thread extending first on one side and then the other of the thread 80 extending between consecutive needle punctures in each row of stitching, and secured by said lines of stitching to the fabric.

3. An ornamental seam for sewed articles, including a fabric, two parallel lines of stitching, an ornamental thread formed in a series of oppositely disposed half twisted loops secured by said lines of stitching to said fabric, a barring thread laid substantially parallel with the line of stitching, the 90 thread extending between consecutive needle punctures lying over said barring threads, whereby they are secured to the fabric.

In testimony whereof I affix my signature, in presence of two witnesses.

VANDIVER J. VAN HORN.
